(Cl. D74—1)

FIG. 1

FIG. 3

FIG. 2

FIG. 1 is a perspective view of a combined clock and memo pad holder showing my new design, a memo pad being shown in broken lines for purposes of illustration;

FIG. 2 is a side elevational view showing the side opposite to that of FIG. 1 as it appears without the memo pad; and

FIG. 3 is a rear elevational view thereof.

The slide rule dial seen on the left in FIG. 1 is actuated by the clock mechanism.

The essential features of the design reside in the portions shown in solid lines on the drawing.

I claim:

The ornamental design for a combined clock and memo pad holder, as shown and described.
